UNITED STATES PATENT OFFICE

WALTER J. BLENKO, OF PITTSBURGH, PENNSYLVANIA, ASSIGNOR TO ARMSTRONG CORK COMPANY, OF LANCASTER, PENNSYLVANIA, A CORPORATION OF PENNSYLVANIA

ROTARY INLAYING MACHINE

Application filed June 21, 1929. Serial No. 372,610.

This invention relates to rotary inlaying machines such as used for the manufacture of inlaid linoleum and provides a flexible control for the machine whereby a wide variety of patterns can be manufactured at relatively low cost.

A rotary inlaying machine comprises a large drum with which are associated two or more die rolls. Webs of linoleum material are fed to the die rolls and knives on the peripheries thereof cut these webs into pattern elements and scrap. The die rolls are provided with strippers whose movement is controlled by pin rolls lying within the die rolls. One of these pin rolls, called the scrap roll, actuates such strippers as are necessary to discharge the unwanted portions of a particular web of material which has been cut up by its die roll. The remaining portions of the cut up web form part of the linoleum pattern to be produced, and are pressed against a backing on the drum of the machine by a so-called pattern roll which actuates the remaining strippers of the die roll.

A set of die rolls for a rotary machine may cost, with its strippers, knives, etc., as much as \$80,000 or \$100,000. Each die roll comprises a cylindrical shell of cast iron having its entire periphery covered by blocks of babbitt metal which are spaced apart a slight distance so that knives may be driven therebetween. These knives are arranged in different ways, depending on the pattern desired, and strippers are placed in the roll between knives through openings provided therefor. These strippers have pins extending into the interior of the die roll, which pins are engaged by the pin rolls as above described. It will be seen from the foregoing that only a relatively limited number of patterns can be made from a given set of die rolls, for any pattern element must conform to the shape of one of the babbitt blocks on the surface of the die roll or to the shape of a plurality thereof.

The pin rolls employed are made up specially for each pattern and the cost of making these rolls, together with the cost of setting up the knives on the peripheries of the die rolls, is very high. If it were possi-

ble to control the pins or other equivalent stripper-actuating means in the various die rolls, it would be possible to materially improve the flexibility of the machine and to decrease the cost of setting it up preparatory to a run. Assume, for instance, that the entire surface of the die roll were divided up by knives so as to cut 1" square blocks. If alternate strippers in each row on the die roll were actuated, there would result a checkerboard pattern made up of 1" squares. If the stripper actuated means were controllable so as to actuate the strippers, say in groups of two, there could be produced a checkerboard pattern of 2" squares. No harm results in making up a 2" square from four 1" squares because linoleum pattern elements are calendered onto the backing and adjacent pattern elements are firmly bonded together. The above example is a very simple one, but will show the wide variety of effects obtainable by control of the strippers instead of the present actuation thereof by pin rolls.

The problem of controlling the strippers is a difficult one because a rotary machine is essentially a high speed one. Only a small fraction of a second is available for actuating the stripper, and the present rotating pin rolls are particularly desirable on this account. The pin rolls lie inside the die roll and are geared thereto. The inwardly projecting stripper pin sweeps out a path of rotation in the die roll, which path is intersected by the path of a pin on the pin roll. The head of a pin on the roll engages the head of the stripper pin and causes it to move outwardly, the entire movement being smooth and devoid of any danger of missing the stripper or bending the pin.

It is highly important that the control of scrap be accurate, for if a piece of the cut-up web designed to be discharged as scrap is inadvertently laid onto the backing, the succeeding die roll attempts to lay a pattern element over this piece of laid-on scrap material, thus seriously affecting the operation.

I provide control means for actuating the stripper, this means preferably comprising a pin roll having movable pins therein and

control means for moving the pins. The pins may be normally arranged so as to throw all of the material to scrap unless they are controlled. This is highly desirable as it 5 prevents breakage of the machine in case anything goes wrong. The pins are preferably magnetically controlled, as this lends itself to the use of master patterns which may be changed as desired. It is also highly desirable 10 in that the available space is very small and the electromagnets and control wires therefor take up a minimum of room as compared with other available types of control.

The pins are preferably arranged to move 15 radially and are biased by a spring, the pins being provided with a shoulder and there being means engaging the shoulder so as to control the path of the pins. Electromagnets are preferably employed for moving the 20 pins so as to cause engagement of the shoulder by the guide means therefor. The guide employed is preferably in the form of a comb made from a metal sheet with slots therein, the sheet being of gently circular cross-section and lying around the pin roll. The pins 25 extend through the slots, and the shoulders are formed by providing collars thereon. If the pins are extended, the collars lie outside the metal sheet and are thus prevented from 30 moving inwardly, while if the collars lie inside the metal sheet, the pins are held in retracted position and cannot move outwardly.

In order to secure the utmost flexibility, 35 there is provided a pin roll having a sufficient number of pins properly spaced to engage every stripper pin in the die roll, these pins being so controlled that the desired strippers are actuated. Two pin rolls are provided, one for discharging scrap, and the other for 40 applying the pattern elements. The pins are preferably biased in both the scrap roll and the pattern roll so that they will tend not to actuate the strippers. However, if desired, the pins may be biased so that they will normally tend to discharge all of the cut-up material. Corresponding pins in the scrap roll 45 and the pattern roll will preferably be actuated by the same control mechanism. There will be an electromagnet for each pin and the 50 same master controller will be employed for both the scrap roll and the pattern roll, it simply being necessary to space the responsive elements in the control system a distance apart corresponding to the distance between 55 the scrap roll and the pattern roll, and while maintaining this spacing causing relative movement between the control elements and the master pattern.

The use of pin rolls having pins for every 60 stripper pin and a master control therefor is also of advantage in that the pattern repeat length may be materially increased. The die roll of a rotary machine as ordinarily constructed has a circumference of 54", but the 65 pin rolls must be materially smaller so as to

fit inside. Ordinarily the pin roll has a diameter such that it rotates three times for every revolution of the die roll. This means that the pattern repeat length in the ordinary machine is only one-third of 54", or 18". This imposes a very material limitation 70 on the variety of products which can be produced on a rotary machine. Where a master pattern is employed, it may be of any length desired and no limitation of pattern 75 length such as is now present is imposed.

The accompanying drawings illustrated more or less diagrammatically a present preferred embodiment of the invention. No attempt is made to show the parts to actual 80 scale, the various elements being shown to such size as will best illustrate the principle.

In the drawings,

Figure 1 is a diagrammatic view illustrating 85 the general layout of a rotary machine;

Figure 2 is a transverse section through a die roll and its associated parts;

Figure 3 is a view to enlarged scale of the scrap roll looking in a direction opposite to 90 that of Fig. 2;

Figure 4 is a developed view, partly broken away, showing the comb which guides the pins;

Figure 5 is an elevation of the comb and 95 the magnet bar;

Figure 6 is a view corresponding to Figure 3 but showing a roll whose pins are biased so that the strippers will tend to eject all of the material from the die roll;

Figure 7 is a fragmentary view corresponding 100 to a portion of Figure 3 but showing a modified comb;

Figure 8 is a diagrammatic view of the master pattern control; and

Figure 9 is an end view showing a modified master control.

Referring first to Figure 1, there is shown a rotary machine comprising a drum 2 supplied with a web of backing material 3, such as burlap. Die rolls 4 are spaced around the drum 2. Each die roll lies adjacent a platen roll 5, and when a web W of linoleum mix is fed between these rolls it is cut up into pieces by knives lying on the surface of the die roll 4. The webs of linoleum mix are supplied from calendars 6 and are carried to the die rolls by belts 7. There is a die roll for each color employed in the pattern. The various pattern elements are laid onto the backing and the linoleum thus formed passes over an inspection table 8 to a calender 9 where the pattern elements are calendered firmly onto the backing 3 and are bonded together, after which the material goes to the stoves for curing.

The machine as thus far described is well known, as is the mechanism for driving the same and for insuring driving of the die rolls and their associated pin rolls at the desired speeds.

Figure 2 shows the improved construction in detail. The die roll 4 comprises a shell 10 having Babbitt blocks 11 over the periphery thereof with knives 12 between the blocks. Strippers 13 lie within each space bounded by the knives 12. These strippers each consist of a top plate 14 mounted on a stripper pin 15. The pin is shouldered as indicated at 16 and is normally held in retracted position by a spring 17. The strippers are made up as individual units, the mechanism being contained in a barrel 18 which is threaded into the shell 10. When the strippers are in position, the pins 15 normally extend inwardly of the shell, as shown in Figure 2. The action of the knives on the web W of material as it passes between the rotating die roll 4 and its platen roll 5 is shown in the upper left hand corner of Figure 2. The knives do not cut entirely through the web, as this would result in the platen roll engaging the knives and dulling them. No matter how carefully the knives are set up, some of them will project a few thousandths of an inch beyond others, and it is therefore usual to provide a clearance of .005" between the die roll and the platen roll. The web is therefore cut nearly through and the cutting is completed by engaging the surface of the material with a stiff brush 18^a which pushes the linoleum down into the space between the knives. When the strippers are actuated the piece above the stripper is pushed outwardly and drops off, being assisted by a rotating brush 19. The scrap falls into a trough 19^a having therein a conveyor, not shown, whereby the scrap is taken away.

The pin roll is indicated generally at 20. It comprises a body 21 having radially extending openings therein to receive pins 22. The pins are carried in barrels 18^b similar to the barrels 18 and are biased outwardly by springs 23, the outward movement being limited by nuts 24 on the pins. Short relatively heavy springs 24^a lie beneath the nuts, as shown.

A comb 25 lies below the pin roll 21 and extends substantially halfway therearound. This comb is formed from heavy metal and is secured to fixed frame members 26 and 27. As best shown in Figure 4, the comb is provided with slots having enlarged end portions 28 and narrow body portions 29. In Figure 3 the extent of the wide and narrow portions is indicated by dotted lines.

The pins 22 are each provided with collars 30 which, when the pins are in their normal outer position, lie a sufficient distance from the body 21 of the pin roll as to project well into the wide portions 28 of the slots when the pin roll is rotated. This action is clearly shown in Figure 3, and it will be seen that throughout the time the pins are traveling within the range of the narrow slots 29, the collars 30 are engaged by the comb 25

and cannot be moved inwardly. As shown in Figure 2, this causes the heads of the pins to engage the stripper pins, thus ejecting material from the die roll. As shown in Figures 2 and 3, the comb is thickened so that when a pin 22 is active the comb imparts an outward movement thereto. The spring 24^a permits this outward movement. This arrangement is of value in that more rapid actuation of the strippers can be effected. The comb is, in effect, a cam which modifies the circular movement of the pins. The springs 24^a limit the outward movement of the pins as determined by the relatively lighter springs 23, but at the same time permit of the additional outward movement determined by the cam action of the comb.

The pins in the scrap roll are so positioned and are in such number that they will engage every stripper pin in the die roll unless controlled. The control mechanism consists of a setting slide 31 mounted in the frame member 27 and having a head 32 adapted to engage the outer end of a pin 22 while it is within the range of the wide slot 28 but before it passes into the narrow slot 29.

There is a slide 31 for each circumferential row of pins 22 in the scrap roll. The slides 31 are normally held in retracted position by springs 33. Electromagnets 34 are provided for each slide 31, and when a magnet is energized, the slide is moved to the left, as viewed in the drawings, so that the head 32 strikes the end of any pin 22 then in position to be engaged. When a pin is thus engaged, it is forced inwardly against the pressure of its spring 23 and is held inwardly until the pin slides off the head 32 of the setting slide 31. The narrow slot 29 terminates at such point that before the pin is out of engagement with the head 32, its collar 30 has been engaged by the edges of the narrow slot 29, thus holding the pin in retracted position during the entire time that it is traveling along the narrow slot. A pin thus retracted will not engage the corresponding stripper pin of the die roll and therefore will not be effective for ejecting a piece of linoleum lying over that particular stripper. A conduit 27^a is provided for the wires leading to and from the magnets 34.

It will be seen from the foregoing that the desirable rotational movement of the stripper-actuating means is retained and that it is only necessary to move the pin in order to effect control. The inertia of the pins is very small and therefore the setting slides 31 can be rapidly actuated as is necessary in a machine of this character. This construction is superior to a construction wherein it is attempted to mechanically operate the strippers themselves because of the greater inertia of the strippers and of the resistance afforded by the linoleum to be ejected.

As shown in Figure 5, the magnets 34 may

be arranged in staggered relationship so as to bring the mechanism into small compass and thus accommodate a pin roll wherein the circumferential rows of pins are placed very close together.

In Figure 7 there is shown a modified comb 25^a which does not have the cam portion formed on its outer surface. Instead of this the comb is of uniform thickness. The arrangement shown in Figures 2 and 3 is particularly desirable if the pin roll is of large diameter, but where a small diameter pin roll is employed the arrangement of Figure 7 will be satisfactory.

15 The pattern roll is indicated generally by the reference character 37. It corresponds in all particulars to the scrap roll and requires no further description.

Figure 6 shows a modification wherein the pins are biased inwardly instead of outwardly. The roll body is shown at 37'. It is provided with collared pins 38 and these are biased inwardly by springs 39. A comb 40 of the general character as the comb 25 is provided, and if the collars of the pins 38 lie within this comb, the strippers are not actuated. This is the normal movement of the pins, and unless they are moved to an abnormal position no strippers will be actuated. The pins are urged outwardly by setting slides 41 mounted in a frame 42 which lies inside of the roll 37. Magnets 43 actuate the setting slides, and they are returned to normal position by springs 44. It will be seen that the operation of this device is exactly the opposite to that of the roll shown in Figures 2 and 3.

Figure 8 shows a control mechanism for the magnets 34. It comprises a drum 45 mounted on a shaft 46 which is driven from the machine at the same angular velocity as the die roll. It is provided with teeth 47 engaging slots 48 in a continuous web 49 of insulating material, such as heavy paper. The drum itself is made of a conducting material and is connected with an electric line wire L^1 through a wire 50 and a collector ring 51. Bars 52 and 53 of insulating material extend along the drum and carry brushes 54 and 55, respectively. The brushes 54 are for the magnets 34 of the scrap roll, and the brushes 55 are for the magnets 34 of the pattern roll. There is a brush for each magnet, each brush being connected to its magnet by a wire 56. The circuit is completed through wires 57 leading to a bus 58 which is connected to the line wire L^2 .

The brushes 54 and 55 are spaced at an angular distance corresponding to the angular spacing of the stripper actuating rolls 20 and 37. The paper has openings 59 punched therein so that when the opening lies below a brush, a circuit is completed, and the magnet is energized. A given opening 59 will first pass under its brush 54 and energize the cor-

responding magnet 34, thus throwing the stripper out of operation and "saving" a piece of linoleum mix. At the time that the die roll rotates a sufficient distance to bring this piece of linoleum in such position that its stripper pin is ready to be engaged by a pin in the roll 37, the web 49 is moved around with the drum 45, but the spacing of the brush 55 from the brush 54 is slightly more than the distance moved by the drum so that the brush 55, instead of making contact with the drum, is insulated therefrom by the paper adjacent the hole 59. Since the magnet for setting the pin in the roll 37 is not actuated, the corresponding pin in the pattern roll will engage the stripper and cause the piece of linoleum to be laid onto the backing 3.

It will be seen that the webs 49 may be changed as desired and that the length of the web will be the pattern repeat length or a multiple thereof. This pattern repeat length may be made much greater than the present standard length of 18", and it will be seen that the only thing necessary for changing the pattern is to change webs 49. There will be a web 49 for each die roll to be controlled.

Figure 9 shows a modified control mechanism wherein instead of a paper web a drum 60 having buttons 61 thereon is employed. Instead of brushes 54 and 55, switches 54^a and 55^a are provided. The connections and the operation are the same as in the apparatus illustrated in Figure 8. However, with the drum mechanism of Figure 9 higher voltages may be employed. The drum 60 is removably mounted on a shaft 46^a whereby it may be replaced when it is desired to change patterns.

It may be necessary to make the pins of the scrap roll and the pattern roll from brass or other non-magnetic material in order to prevent their being improperly controlled by the magnets 34.

Figure 2 shows at the top thereof the customary lubricating roll 62 which is effective for moving all of the strippers so that the surfaces thereof will be engaged by a brush 63 and lubricated with paraffin oil to prevent sticking of the linoleum thereto.

I have illustrated and described a present preferred embodiment of the invention and certain modifications thereof. It will be understood, however, that it is not limited to the forms shown but may be otherwise embodied within the scope of the following claims.

I claim:

1. In a rotary inlaying machine, a die roll, a stripper therein, a stripper roll, actuating pins on the stripper roll, the pins being movable into or out of stripper engaging position, and means for controlling the movement of the pins prior to their engagement with the stripper.
2. In a rotary inlaying machine, a die roll,

- strippers therein, a stripper roll, pins slidably mounted in the stripper roll, but radially movable therein so as to be in or out of stripper engaging position, and means for radially moving a pin prior to its engagement with the stripper.
3. In a rotary inlaying machine, a die roll, strippers therein, stripper-actuating means, and means other than the stripper for moving the stripper-actuating means in a non-circular path.
4. In a rotary inlaying machine, a die roll, strippers therein, stripper-actuating means, means other than the stripper for moving the stripper-actuating means in a non-circular path, and means for changing the path.
5. In a rotary inlaying machine, a die roll, strippers therein, stripper-actuating means comprising a supporting roll and pins movable therewith, and a cam for moving the pins.
6. In a rotary inlaying machine, a die roll, strippers therein, scrap discharge means for actuating the strippers, the scrap discharge means being movable in a path to normally actuate a stripper and cause discharge of scrap, pattern forming means for actuating a stripper, and a common means for controlling said pattern forming means.
7. In a rotary inlaying machine, a die roll, a stripper therein, a stripper roll having an actuating pin therein, means normally urging the pin outwardly, and means for moving the pin inwardly.
8. In a rotary inlaying machine, a die roll, strippers therein, a pin roll, a pin radially movable therein, and means for holding the pin in adjusted position during a portion of the revolution of the die roll, said portion of revolution commencing prior to the engagement of the stripper by the pin.
9. In a rotary inlaying machine, a die roll, strippers therein, a pin roll, a pin radially movable therein, means for holding the pin in adjusted position during a part of the revolution of the die roll, and means other than the stripper for effecting the movement of the pin.
10. In a rotary inlaying machine, a die roll, strippers therein, a pin roll, a pin radially movable in the pin roll, the pin having a shoulder, and a guide extending around the pin roll and engaging the shoulder.
11. In a rotary inlaying machine, a die roll, strippers therein, a pin roll, a pin radially movable in the pin roll, the pin having a shoulder, and a guide extending around the pin roll and engaging the shoulder, the guide having a cam face formed thereon.
12. In a rotary inlaying machine, a die roll, strippers therein, a pin roll, a pin movable therein, a collar on the pin, and a guide extending around the pin roll and adapted to be engaged by the collar on its inner or its outer side.
13. In a rotary inlaying machine, a pin roll, a movable pin therein, and means for biasing the pin.
14. In a rotary inlaying machine, a die roll, a stripper therein, and magnetic means for actuating the stripper.
15. In a rotary inlaying machine, a die roll, strippers therein, stripper moving means for different strippers, and magnetic means for controlling the several last mentioned means.
16. In a rotary inlaying machine, a die roll, strippers therein, scrap forming means for actuating strippers, pattern forming means for actuating strippers, and a single control means for the scrap forming and pattern forming means.
17. In a rotary inlaying machine, a die roll, strippers therein, a plurality of stripper actuating means, pattern control means having a plurality of control members corresponding to different stripper-actuating means, and means operatively connecting the control members to the stripper-actuating means.
18. In a rotary inlaying machine, a die roll, strippers therein, scrap discharge means for actuating strippers, the scrap discharge means being movable in a path wherein they actuate the strippers and cause discharge of the scrap, and being also movable in another path wherein they leave the strippers unaffected, and means for directing the scrap discharge means into one or the other of said paths.
19. In a rotary inlaying machine, a die roll, strippers therein, scrap discharge means for actuating strippers, the scrap discharge means being movable in a path wherein they actuate the strippers and cause discharge of the scrap, and being also movable in another path wherein they leave the strippers unaffected, means for directing the scrap discharge means into one or the other of said paths, and cam means lying in the first-mentioned path for effecting movement of the scrap discharge means.

In testimony whereof I have hereunto set my hand.

WALTER J. BLENKO. 115
